UNITED STATES PATENT OFFICE.

ELIE BELINE, OF NEW YORK, N. Y.

MESH-BAG.

1,074,237.

Specification of Letters Patent. Patented Sept. 30, 1913.

Application filed September 29, 1911, Serial No. 651,916. Renewed May 6, 1913. Serial No. 765,909.

To all whom it may concern:

Be it known that I, ELIE BELINE, a subject of the Czar of Russia, residing in the borough of the Bronx, city, county, and State of New York, have invented certain new and useful Improvements in Mesh-Bags, of which the following is a specification, reference being had to the accompanying drawings.

10 This invention relates to improvements in mesh-bags; and an object of this invention is to provide means for attaching the mesh to the frame at the joints of the latter.

In the drawings illustrating the principle 15 of this invention and the best mode now known to me of applying that principle, Figure 1 is an elevation of my new mesh-bag; Fig. 2 is a detail showing in side elevation the hinged part of the frame with 20 the mesh attached; Fig. 3 is a view similar to Fig. 2 but with the mesh removed; Fig. 4 is a detail showing in end elevation the joint 25 shown in Fig. 3; Fig. 5 is a detail showing in perspective the joint illustrated in Figs. 3 and 4; and Fig. 6 is a detail in elevation showing the joint as viewed from inside the frame when the same is open.

The frame *a* is on its inside along its top 30 *b* and sides *c* provided with eyes *d* to which the mesh is attached in the usual manner. The end of each side part *c* is formed with a flange or rib *e* from which projects a hinge-lug or ear *f*; and adjacent side parts are pivotally connected together by passing 35 a hinge-pin *g* through their coöperating hinge-lugs *f*. The ribs *e* limit the opening movement of the frame-members. Parallel with and outside of each rib *e* there is arranged on the end of the side part a series 40 of eyes *h* which lie in planes substantially

perpendicular to the rib; and at the outer end of each rib *e* there is provided an eye *i* which lies in practically the same plane with the rib and, therefore, at substantially right angles with the eyes *h*. To the eyes *h*, 45 *i* are attached the part of the mesh *j* at the joint, which is thus covered and an artistic and sightly appearance is given to the bag. Moreover, this arrangement permits the free opening of the joint, while covering the 50 same.

I claim:

1. A mesh-bag having mesh-carrying frame members hinged together and formed with ribs at the hinge-joint and with eyes 55 upon the ribs for the attachment of the mesh, whereby the latter covers the joint.

2. A mesh-bag having mesh-carrying frame members hinged together and formed with ribs at the hinge-joint and with eyes 60 which project from the ribs in planes substantially perpendicular to the same and to which the mesh is attached to cover the hinge joint.

3. A mesh-bag having mesh-carrying 65 frame members hinged together and formed with eyes at the joint, to which eyes the mesh is attached to cover the joint.

4. A mesh-bag having mesh-carrying frame members hinged together and formed 70 with ribs at the hinge-joint and with eyes which project from the ribs in planes perpendicular and parallel to the ribs and to which the mesh is attached to cover the joint.

ELIE BELINE.
